UNITED STATES PATENT OFFICE.

CHARLES E. BAKER, OF HARTFORD, CONNECTICUT, ASSIGNOR TO THE UNIVERSAL PATTERN & MODEL COMPANY, OF HARTFORD, CONNECTICUT, A CORPORATION OF CONNECTICUT.

DESIGN FOR A CHILD'S VEHICLE.

Application filed February 26, 1921. Serial No. 448,252. Term of patent 7 years.

To all whom it may concern:

Be it known that I, CHARLES E. BAKER, a citizen of the United States, residing in Hartford, in the county of Hartford and State of Connecticut, have invented a new, original, and ornamental Design for Child's Vehicle, of which the following is a specification, reference being had to the accompanying drawing, forming part thereof.

Said drawings represent in—

Figure 1 a plan view of a child's vehicle showing my new design.

Figure 2 a side view of the same.

Figure 3 a view looking from the rear end.

Applicant's invention resides in the entire article comprised in the shape or outline of the body of the structure, many of the customary parts of the device being illustrated thereon by picture.

I claim:

The ornamental design for child's vehicle, as shown.

CHARLES E. BAKER.
